United States Patent Office

Des. 211,583
Patented July 2, 1968

211,583

GAME TABLE OR THE LIKE

George E. Schaefer, Muskegon, Mich., assignor to Brunswick Corporation, Chicago, Ill., a corporation of Delaware

Filed June 29, 1967, Ser. No. 7,635

Term of patent 14 years

(Cl. D33—14)

Fig. 1.

FIG. 2.

FIG. 3.

FIG. 1 is a perspective view of a game table or the like embodying my new design, showing the octagonal top, four sides of the top and two sides of the supporting pedestal;

FIG. 2 is an elevational view taken from the rear of the table as illustrated in FIG. 1, showing three additional sides of the octagonal top and one additional side of the supporting pedestal; and

FIG. 3 is a sectional plan view taken at about the line 3-3 of FIG. 2.

The side of the table top not shown is like those shown and the side of the supporting pedestal not shown is like those shown.

I claim:

The ornamental design for a game table or the like, as shown and described.
